UNITED STATES PATENT OFFICE.

EDWARD A. HENKLE, OF PHILADELPHIA, PENNSYLVANIA, ASSIGNOR TO GLOBE TICKET COMPANY, OF PHILADELPHIA, PENNSYLVANIA, A CORPORATION OF PENNSYLVANIA.

COUPON-TICKET.

1,253,033.

Specification of Letters Patent. Patented Jan. 8, 1918.

Application filed May 15, 1917. Serial No. 168,782.

To all whom it may concern:

Be it known that I, EDWARD A. HENKLE, a citizen of the United States, residing at Philadelphia, in the county of Philadelphia and State of Pennsylvania, have invented new and useful Improvements in Coupon-Tickets, of which the following is a specification.

This invention relates to improvements in theater or similar admission tickets of the type wherein a body portion to be retained by the doorkeeper is provided with a detachable end coupon to be retained by the seat holder.

15 The invention consists in a ticket having similar end coupons and a body portion located centrally between the coupons, and wherein both faces of the ticket are similarly printed and the obverse and reverse faces of 20 the respective coupons are parts of each face of the ticket. There is thus provided a ticket wherein either end constitutes a coupon and each coupon will contain on its two faces designations of all material or 25 necessary data, such as the date, the name of the theater, and the price and location of the seat, wherein both coupons may be detached without destroying the body portion, and wherein the body portion will also carry 30 designations of all data material thereto.

By providing a ticket of this character the operation of detaching the seat holder's coupon is facilitated because either side of the ticket serves as the face thereof and 35 either end of the ticket serves as the seat holder's coupon; but one composition of type is required for the printing of the ticket because the printed matter is identical on both faces of the ticket; the coupons are 40 more easily read and of greater informative value because both faces are available for the data, part of which is printed on one face and the remainder on the other face, and the printing is in larger type and better 45 arrangement than is possible with tickets of existing constructions; and provision is made for keeping a record of advance sales and for checking the tickets taken at the door, because one of the coupons may be detached by the ticket seller and retained as a 50 record of the sale, the other coupon may be detached by the doorkeeper and retained by the seat holder, and the body portion, when

both coupons have thus been detached will be left intact and with all of its data unimpaired.

An embodiment of the invention is illustrated in the accompanying drawing, wherein:—

Figure 1 is a view of one face of a theater ticket in which the features of the invention are incorporated; and

Fig. 2 is a view of the opposite face, the ticket being turned over about its longer dimension as an axis.

Similar characters of reference designate corresponding parts in the two views.

It is to be understood that the invention is applicable, generally, to coupon tickets, although it is particularly advantageous when applied to coupon tickets of the kind used in theaters and the like wherein it is desirable that the detached coupon and also the remainder or body of the ticket should contain the important or necessary designations pertaining to the seat to which the ticket corresponds, such as the date for which the ticket was issued for use, the location of the seat, and its price. The ticket shown in the present instance is an example of a theater ticket embodying the present invention, and while it represents the preferred embodiment of the invention, it is to be understood that the invention is not restricted to the precise arrangement shown, as equivalent arrangements are contemplated and will be included within the scope of the claims.

In the ticket as shown, 1 represents the card or slip, usually of paper or cardboard of suitable thickness which may be considered as divided into a body 2, and end coupons 3 and 4, the coupons in such case being detachable substantially along lines 5—5. To facilitate such detachment, the card may be indented or otherwise weakened along said lines, although such is not ordinarily necessary. On the face A, shown in Fig. 1, the main or body portion 2 has printed thereon designations of the date for which the ticket was issued and the name of the theater or place where the ticket is to be used, the lines of printing preferably extending longitudinally of the ticket; the coupon 4 has printed thereon as at Y similar designations, and the coupon 3 has printed thereon as at X designations of the

identity of the seat, the part of the theater in which the seat is located and the price of the ticket, the lines of printing on the coupons preferably extending transversely 5 of the ticket.

In Fig. 2 the ticket is represented as turned over about its longitudinal center and its opposite face B is shown. This face is printed from the same composition of type 10 and the printed matter is identical with that on the face A. There is a reversal, however, of the printed matter on the coupons, that is to say, the coupon 3 on the face B bears the matter Y printed on the face A of the coupon 4 and the coupon 4 on the face B bears the matter X printed on the face A of the coupon 3.

The printed matter on the two coupons 3 and 4 is identical and either coupon may be 15 indifferently detached and given to the seat holder. Since the printed matter is distributed, in parts X and Y on both coupons, said matter may be displayed in larger type and in more convenient or readable arrangement 20 than is possible with existing constructions. The printed matter on the coupons may also be more comprehensive, that is to say, it may include items which, owing to the limitations 25 of space, cannot be practically displayed on the coupon of tickets of existing construction, for example, the price of the ticket. This is a consideration of great practical 30 value since in some States legislation has been, and is about to be, enacted, requiring 35 that the price of the ticket be printed on the seat holder's coupon.

Instead of using the ticket in the manner above described, that is to say, by issuing the ticket to the purchaser with both coupons 40 thereon, either of these coupons being detached when the ticket is presented to the doorkeeper, one of the coupons, at the time the ticket is sold or issued, may be detached and retained by the ticket seller to provide 45 a record of the advance sale of tickets. This consideration is also of great practical value and, so far as I am aware, cannot be satisfactorily served by any tickets of existing constructions. Where a coupon is thus retained by the ticket seller, the ticket will be 50 issued to the purchaser with a single coupon which is detached from the body portion similarly to the coupon of an ordinary ticket but which carries fuller and more conspicuously displayed data than the coupon of an 55 ordinary ticket.

In any case, the coupon retained by the purchaser or holder of the ticket will contain such complete information as to avoid

any dispute as to his right to the seat occupied by him.

Owing to the arrangement of the body portion 2 between the coupons said body portion will be intact, whether only one or both of the coupons be detached and as retained by the doorkeeper will, therefore, constitute a record of the ticket delivered at the door. It will usually be sufficient for the record afforded by the body portion 2 to be merely of the name of the theater, the date 65 and time of the performance and the part of the theater (indicated by the color of the ticket), in which the seat is located, but it will be obvious that the matter printed on the body portion may be as comprehensive 70 as desired.

I claim:—

1. An admission ticket comprising a card having a body portion and coupons at the opposite ends of the body portion and detachable therefrom, the body portion being located between the coupons whereby it is left intact upon the removal of one or both of the coupons, the coupons bearing identical printed matter but each coupon having its 85 printed matter different on its obverse and reverse faces, the obverse face of one coupon and the reverse face of the other coupon being parts of each and the same face of the ticket, the body portion having printed 90 thereon data pertinent to a record of the tickets taken up, and the coupons having printed thereon data pertinent as information for the seat holder.

2. An admission ticket comprising a card 95 having a body portion and coupons at the opposite end of the body portion and detachable therefrom, the body portion being located between the coupons whereby it is left intact upon the removal of one or both 100 of the coupons, the coupons bearing identical printed matter and each coupon having on its obverse face designations of the location 105 of the seat and on its reverse face designations of the date, the obverse face of one coupon and the reverse face of the other coupon being parts of each and the same face of the ticket, the body portion having printed 110 thereon data pertinent to a record of the tickets taken up, the printing on both faces of the tickets being identical.

In testimony whereof I have hereunto set my hand in presence of two subscribing witnesses.
